Elmir J. Key, of Lowell, Mass.

Assignor to

The Lowell Manufacturing Company,
Letters Patent No. 1631, dated Aug. 12, 1862.

The schedule referred to in these Letters Patent and making part of the same,

To all whom it may concern;

Be it known that I, Elmir J. Key, of Lowell in the County of Middlesex, and state of Massachusetts, have originated and designed a new Pattern for Carpets or other fabrics, of which the following is a full, clear and exact description, reference being had to the accompanying drawings, making part of this specification.

In corner A, is one fourth of a set group of flowers resting on the ground, 1, which is enclosed by the band of irregular lines 2.

In corner B, is one fourth of a large block resting on the ground 3, which is enclosed by the band of irregular lines 4.

In corner C, is one fourth of a set figure resting on a regular ground work enclosed by the broad frames 5, which support the scroll figures. In corner D, is a ground of leaves and small lines enclosed by the broad frame 6, which also supports four large scroll figures one fourth of which are shown in the drawing.

Fig. 1, in the centre is a heavy flower supported by a branch of leaves, small flowers and sprigs.

The remaining parts of the design are sprigs which radiate from the scroll figures of the frames 5 and 6.

The colors employed for the different portions of the
